RICHARD M. HOPKINS, OF RUTHERFORD, NEW JERSEY, ASSIGNOR TO AMERICAN DISTRICT TELEGRAPH COMPANY, OF JERSEY CITY, NEW JERSEY, A CORPORATION OF NEW JERSEY.

KEY DEVICE FOR REGISTERS.

1,394,831.

Specification of Letters Patent.

Patented Oct. 25, 1921.

Application filed June 12, 1919. Serial No. 303,633.

To all whom it may concern:

Be it known that I, RICHARD M. HOPKINS, a citizen of the United States of America, and resident of Rutherford, county of 5 Bergen, and State of New Jersey, have invented a Key Device for Registers, of which the following is a specification.

My invention relates to improvements in keys, or key devices, more particularly to 10 the key devices or watchmen's register conditioning devices designed to be used in connection with the watchmen's register of a companion application by C. C. Johnson and R. M. Hopkins, Serial Number 303,393, filed 15 June 12, 1919 and itself constituting an improvement on the register of the application of C. C. Johnson, Sr. No. 209,279, filed Dec. 28, 1917. According to the said Johnson system, the watchman is provided with a 20 portable register having registry mechanism adapted to be actuated by the watchman each time the latter reaches a station which he is supposed to visit; but the registry mechanism is normally locked, and can be 25 actuated only when the watchman has applied his register to a suitable key device, or "conditioning device," of which there is one at each station to be visited. The several key devices are preferably provided 30 with means whereby they are differentiated one from another, and the mechanism of the register is such that actuation of the registry mechanism at one station conditions that mechanism for actuation upon application 35 to the next key device of the series.

While the several key devices must be readily accessible, in the sense that it must be easy to apply the watchman's register thereto, yet the essential portion of the key 40 device, or key proper, should be protected from the elements, and from accidental injury; hence it is desirable to provide a suitable case. It is still more important that this essential portion, or key proper, shall 45 be so protected that it is extremely difficult, if not impossible, for the watchman, or other unauthorized person, to learn the actual construction of the key device, and in particular to learn the construction, size, and arrangement 50 of those parts of the key device which, by engagement with corresponding parts of the register, effect the release of the mechanism of the latter for actuation. It is

further desirable that the construction of the key device be such that, if that device be 55 taken apart by an unauthorized person, it shall be extremely difficult, if not impossible, to reassemble it again except by the aid of special tools which the unauthorized person is not likely to have available. In this way 60 any attempt to learn the construction of the key device and so learn how to construct a successful imitation thereof, will be exposed. It should be stated that according to the Johnson system, the watchman's register 65 must be applied to the several key devices in proper order; and if application of the register to any one key device be omitted, the register cannot be operated at other key devices of the system; hence if one of the 70 key devices be dismounted or otherwise destroyed, so as to be incapable of engagement with the register, the watchman cannot operate his register at other key devices of the system, but must at once announce the 75 disassembly of the key device; furthermore, the system is such that the watchman must, from time to time, transmit a signal to a central or supervising station, and cannot do this unless his register has been operated correctly 80 at every preceding station of the system; so that if the watchman fails to report the disassembly of a key device, he cannot send in the required signal, and this in itself exposes his delinquency.

My present invention relates to means whereby the key device proper is protected and whereby, if it be tampered with, it falls apart so as to be incapable of operating in connection with the register; thus necessitating reporting its disassembly, as previously explained. My invention consists in the novel construction of the key device proper, also in the novel construction of its protecting casing.

I will now proceed to describe my invention with reference to the accompanying drawings, in which one embodiment of my invention is illustrated, and will then point out the novel features in claims. In the 100 said drawings:

Figure 1 shows a side elevation of the key device; Fig. 2 a front elevation thereof; Fig. 3 a rear elevation thereof; Fig. 4 a central longitudinal section thereof, and 105 Fig. 5 a transverse section on the line 5-5

of Fig. 1. Fig. 6 is a fragmentary perspective elevation of certain portions of the key device proper, illustrating the "fall apart" feature thereof.

5 The key device comprises a suitable base, 41, consisting of two separable parts, 41^a and 41^b. To this base is secured a protecting casing, or shell, 42, for protecting the key-device proper, 43. While of course the particular register with which this key device 10 is to be used forms no portion of the present invention, and therefore its construction need not be illustrated, yet it may be mentioned that this register is, in form, a hollow-shafted key, the said shaft being adapted 15 to be passed over the key-device proper, so that certain pin tumblers carried by said key-shaft may be engaged and actuated by pin-tumblers 44 with which said key-device 20 is provided. Also, the said shaft of the register is provided with certain projecting lugs, to receive which the shell or casing 42 is provided with a slide-way 46.

The pin tumblers 44 are mounted, as is 25 usual in pin-tumbler locks, in suitable pockets in which are springs 44^a tending to press them out. A suitably-perforated sleeve 45 normally retains them in their pockets.

The section 41^a of the base is provided 30 with screw-holes through which may be passed screws to fasten the section 41^a to a wall or other support. Said section 41^a is also provided with an annular pocket 41^{a'} to receive the heads of these screws. The 35 section 41^b of the base has a flange 41^{b'} embracing section 41^a, and 41^b is held to 41^a by screws 41^{b''}. The shell 42 is secured to section 41^b by screws 42^a, inserted from the rear side of 41^b. This shell 42 has a front 40 flange 42' which closes the front of the shell except for the central opening for the insertion of the shaft of the register, and except for the slot, forming the front of the slide-way 46, for the reception of the lugs of the register. Therefore, while of necessity the shell must have a front opening for the reception of the register, still it makes 45 access to the key-device 43 very difficult, and in particular makes it practically impossible to take a wax impression of that key device. Furthermore, if a wax impression should be taken of the key device, almost inevitably one or more of the tumblers 44 would be depressed, and would remain stuck fast in the 50 depressed position, due to adhesion of wax to the tumbler and to the sides of the corresponding perforation of sleeve 45. The construction of the register to be used with this key device is such that for the operation 55 of the register, the action of the pin-tumblers on corresponding tumblers of the register is required; hence if one of the tumblers of the key device remain stuck in depressed position the register cannot be 60 operated. The shell 42 can be removed from

the base to afford access to the key device proper, only by removing screws 41^{b''} and separating 41^b from 41^a; and if this be done, the screw-heads will usually present evidence of tampering. It is quite possible to 70 grasp the sleeve 45 with suitable pliers and pull said sleeve out, the tumblers 44 being held depressed, if necessary, while this is being done, by an instrument inserted through slide-way 46. But this involves 75 tearing the sleeve from its base 49, or tearing said base from its holding screws; moreover if the sleeve be removed the tumblers will be forced out of their sockets at once by the springs behind them, as illustrated 80 in Fig. 6, and will drop down within the shell. Even if the tumblers be recovered thence, it is almost impossible to replace them in their sockets, and then, while holding them in place, force back the sleeve 45, 85 without first removing the shell 42. Moreover, if the sleeve has been torn from its base, or from its holding screws, evidence of tampering cannot well be removed.

It will be recalled that it has been stated 90 previously that according to the system in which these key-devices are to be used, the register must be applied to the several key-devices in proper order, and if operation of the register at any one key-device be omitted, the register cannot be operated at other key-devices, nor can the required signal be sent in. The watchman has, at best, little time available for tampering with any one key device. If he derange any one key device, he can not send in the required signal, at the end of his tour, and immediate detection results.

The key device proper, 43, is provided at its inner end with a rounded end 43^a, and 105 with a groove 43^b. It is mounted in a suitable orifice in base section 41^a, and this base section is provided with springs 47 adapted to engage groove 43^b and so hold the key device in place. It is obviously an easy matter 110 to attach these key devices proper to their bases.

It has been stated above that this key device is intended for use in connection with a register of a certain application by C. C. 115 Johnson and R. M. Hopkins, Serial No. 303,593. That register comprises a certain tubular body with projecting lugs, the whole being adapted for insertion into the key device of this application, the said lugs fitting 120 into the slide-way 46 and the said tubular body passing over the spindle 43, and depressing the tumblers 44 as it slides over the spindle. The said register is provided with certain internal tumblers, with which the 125 tumblers 44 of the key device coact.

What I claim is:—

1. A key-device such as described, comprising a fixed base having a recess to receive the end of a spindle, and means in said 130

recess to engage and permanently retain the spindle, and a tumbler-carrying spindle adapted to be inserted into said recess.

2. A key-device such as described, comprising a fixed base having a recess to receive the end of a spindle, and a tumbler-carrying spindle adapted to be inserted into said recess, and spring means within said recess adapted to grip said spindle when so inserted and permanently retain it.

3. A key-device such as described, comprising a fixed two-part base, one member of which is adapted to be secured to a suitable support and is provided with a recess adapted to receive the end of a spindle, said member being provided with means for permanently retaining the spindle when so inserted, the other member of said base being arranged to cover said first member, and a tumbler-carrying spindle the end of which is inserted into said recess.

4. A key-device for registers such as described, comprising a stem and a support

therefor, said stem provided with tumbler-pockets, and pin tumblers yieldingly mounted in said pockets. 25

5. A key-device for registers such as described, comprising a stem and a support therefor, and a shell surrounding said stem and having an opening in front for the insertion of the register, said stem having tumbler-pockets, and tumblers yieldingly mounted in said pockets. 30

6. A key-device for registers such as described, comprising a stem and a support therefor, and a shell surrounding said stem and having an opening in front for the insertion of the register and a guide-way for the reception of a lug of the register. 35

In testimony whereof I have signed this 40 specification in the presence of two subscribing witnesses.

RICHARD M. HOPKINS.
